UNITED STATES PATENT OFFICE.

HENRY EUGENE THOMPSON, OF CHICAGO, ILLINOIS.

GASOLENE-ENGINE.

No. 803,078.

Specification of Letters Patent.

Patented Oct. 31, 1905.

Application filed February 8, 1905. Serial No. 244,769.

To all whom it may concern:

Be it known that I, HENRY EUGENE THOMPSON, residing at Chicago, in the county of Cook and State of Illinois, have invented certain new and useful Improvements in Gasolene-Engines, of which the following is a specification.

My invention relates to certain new and useful improvements in gasolene-engines; and it more particularly relates to gasolene-engines of the two-cycle type. The present invention has for its object to provide an engine of this character of a very simple construction which will readily and effectively serve its intended purposes.

My invention also has for its object to provide a special type of valve controlling the admission of working agent into the explosion-chamber in such a manner to prevent the new charge becoming prematurely ignited as it passes from the valve into the explosion-chamber.

With other objects in view, which will be hereinafter more fully apparent, the invention includes certain novel construction, operation, and arrangement of parts, all of which will be first described in detail and then specifically pointed out in the appended claims, reference being had to the accompanying drawings, in which—

Figure 1 is a perspective view showing my invention as applied for use as an automobile-engine. Fig. 2 is a longitudinal section thereof. Fig. 3 is a longitudinal cross-section on the line 3 3 of Fig. 2. Fig. 4 is a cross-section on the line 4 4 of Fig. 2. Fig. 5 is a similar view on the line 5 5 of Fig. 2. Fig. 6 is a detail sectional view of the inlet-valve. Fig. 7 is an enlarged sectional view of the improved form of valve in the piston. Fig. 8 is a side elevation thereof. Fig. 9 is a detail view of the wire-gauze member hereinafter referred to. Fig. 10 is an inverted plan view of the valve shown in Fig. 7.

Referring now to the accompanying drawings, in which like characters of reference indicate like parts in all the figures, 1 designates the engine-casing, which is preferably constructed in two sections, the fly-wheel-casing section 1^a and the piston-casing 1^b, and these two sections 1^a 1^b are bolted or otherwise secured together, as at 1^c, by the rims or flanges 1^d of the sections 1^a 1^b, respectively.

The piston-casing 1^b is centrally bored to form a chamber 1^e, divided into two parts by the piston 2, one part forming the explosion-

chamber. The piston 2 reciprocates in the chamber 1^e from substantially one end to the other.

About midway the length of the chamber 1^e the casing-section 1^b is provided with exhaust-apertures 1^h 1^h, which discharge into the exhaust off-takes 1^m 1^m, as clearly shown in Fig. 2 of the drawings.

One end of the casing-section 1^b is closed by the end wall 1ⁿ and provided with a water-jacket for cooling the working end of the chamber 1^e.

4 designates any suitable igniting mechanism which is located at the closed end of the casing 1^b and which igniting means may be of the electric type, as shown, or of any other approved type, as the same *per se* forms no part of my present invention.

The piston 2 comprises a cylindrical member having an end (the end adjacent the explosion-chamber) closed by a wall or diaphragm 2^a, which wall or diaphragm 2^a is centrally apertured, as at 2^b, and screw-threaded to receive the valve 5, which will be herein-after more fully explained and again referred to.

2^c 2^d designate internally-projecting radial hubs which are formed on the interior of the pistons and which are longitudinally apertured, as at 2^d 2^d, to receive the transverse shaft 2^e, which shaft 2^e also passes through the walls of the pistons 2 and also through the bearing portion 6^a of the piston-rod 6, which piston-rod bearing 6^a is provided with an internal lining 6^x of bearing metal, as clearly shown in Fig. 2 of the drawings.

The fly-wheel chamber 1^a has lateral bearing portions 1^x 1^x, lined with bearing metal 1^y 1^y, to receive the drive-shaft 7 7, and the ends 7^a 7^a of the said drive-shaft 7 7 project into the casing 1^a and into the fly-wheel chamber 1^z and receive the fly-wheels 8 8. The fly-wheels 8 8 are suitably keyed to the ends 7^a 7^a of the shafts 7 7, as at 8^a 8^a, so that the fly-wheels and shafts will turn together. The fly-wheels 8 8 are cored out, as at 8^b 8^b, to form hollow chambers within the fly-wheels, which chambers are, however, so formed as to be air-tight to prevent the working agent entering therein. The reason I prefer to core out the fly-wheels is that by so doing I confine the greater portion of their weight at their periphery 8^c 8^c, and thereby increase their efficiency.

The fly-wheels 8 8 are spaced apart to leave a passage x between them and allow the

piston-rod 6 to also pass between the fly-wheels 8 8.

8^d 8^d designate hubs integrally formed with and passing through the fly-wheels, and these hubs receive the communicating shaft 9, which shaft 9 also passes through the bearing end 6^h of the piston-rod 6. The hubs 8^d 8^d are also countersunk, as at 8^e 8^e, to receive the ends 6^e 6^e of the bearing portions 6^b 6^b of the piston-rod 6, as clearly shown in Fig. 2 of the drawings. The bearing 6^b is provided with a suitable lining 6^d of bearing metal.

The casing-section 1^a is preferably formed in two halves, as shown in the drawings, to permit the ready assembling of the parts therein, and these two halves 1^r 1^r may be bolted or otherwise secured together, as at 1^s and as clearly shown in Figs. 1 and 2 of the drawings.

10 10 designates an inlet-valve of any approved construction for admitting the working agent to the fly-wheel chamber, and the said valve 10 is in the nature of a one-way valve arranged to operate only to admit the working agent into the fly-wheel chamber and prevent its escape therefrom due to back pressure.

The valve 5, which is of a special construction, forms an essential part of my invention and comprises a cylindrical body 5^a, forming 30 the valve-casing and having a rim 5^b and a threaded portion 5^b for engaging the threaded aperture 2^b of the piston 2. The valve-casing 5^a is also provided with a transverse web 5^c to form the valve-seat 5^d for the head 5^e of the 35 valve proper, and the valve-head 5^e has an integrally-formed stem 5^f, which carries a disk portion 5^g at its opposite end and is provided with a coil-spring 5^m, which engages said disk and also engages a disk 5ⁿ, which is held in 40 the seat 5^p of the casing 5^a, and the disk 5ⁿ is provided with a valve-stem bearing 5^r, as clearly shown in Fig. 7 of the drawings. The valve-casing 5^a is extended to form a chamber below the web 5^c, and this chamber is in communication with the interior of the piston 2 by means of the apertures 5^x of the wall of the valve-casing 5^a. Arranged in the chamber below the web 5^c is a gauze diaphragm, which is preferably bent into a spherical section, and 45 50 55 55 the gauze member 5^y has its peripheral rim seated in the groove 5^z on the under side of the web 5^c, while the valve-stem-bearing member 5^r passes through an aperture 5^y in the diaphragm 5^y.

55 The disk 5ⁿ is held in position by swaging over the edge of the valve-casing in several places, as at 5^p. (See Figs. 7 and 10 of the drawings.)

60 By providing the diaphragm 5^y in the valve member 5 I prevent the working agent within the piston 2 and within the fly-wheel chamber from becoming ignited by the burned mixture in the explosion-chamber as the new mixture passes through the valve 5 into the explosion-chamber after the burned mixture has been ex-

hausted. This prevents the premature ignition of the new charge.

So far as described the manner in which my invention operates will be best explained as follows: Assuming the parts are in the position shown in Fig. 2, the exploded charge having passed out of the explosion-chamber through the exhaust-aperture 1^h 1^h and a new charge as having entered through the valve 5 into the explosion-chamber while the piston 2 is commencing its stroke in the direction of the arrow in Fig. 2, now as the piston 2 continues its stroke the apertures 1^h 1^h will be closed, and the piston 2 will compress the new charge ahead of it. At the same time the fly-wheel chamber will be filled with working agent entering through the valve 10 as the piston moves forward. As the piston reaches the end of its stroke in the direction of the arrow *a* in Fig. 2 the compressed charge is exploded, and thus forces the piston on its return stroke in the direction opposite to that of the arrow in Fig. 2. As the piston continues on its return stroke it compresses the working agent within the fly-wheel chamber, which, however, cannot pass through the valve 5 until the exhausts 1^h 1^h are uncovered by the piston 2 and the burned mixture has passed out of the explosion-chamber. As soon as the burned mixture passes out of the apertures 1^h 1^h the valve 5 automatically opens to admit the compressed charge of new working agent to the exploding-chamber, it being understood that the piston 2 closes the apertures 1^h 1^h as soon as the burned mixture passes out. The 100 operation of the engine then continues as before.

From practical experience I have found that in using an engine of this type without the screen-diaphragm in the valve 5 the working agent becomes ignited as it passes through the valve 5, and when I use the wire-gauze screen such ignition of the working agent does not occur, the screen serving as a fire-shield between the explosion-chamber and the fly-wheel chamber.

The water-jacket around the explosion-chamber serves to keep the said chamber cool and prevent overheating thereof.

From the foregoing description, taken in connection with the accompanying drawings, it is thought the complete construction, operation, and many advantages of my invention will be readily apparent to those skilled in the art to which it appertains, and I desire it understood that slight changes in the detailed construction, arrangement, and operation of parts may be readily made without departing from the scope of the invention or the appended claims.

Having thus described my invention, what I claim, and desire to secure by Letters Patent, is—

1. An engine of the character stated comprising a casing, a fly-wheel rotatably mount-

ed within the casing, a piston reciprocally mounted within the casing and dividing the casing into a first chamber and an explosive chamber, a piston-rod connecting said piston to said fly-wheel, means for admitting working agent into the first chamber, a valve in the piston for admitting the working agent into the explosion-chamber at predetermined times, said explosion-chamber having exhaust-outlets closable by said piston, and means for exploding said working agent within the explosion-chamber at predetermined times, said valve in the piston comprising a casing having an internal web forming a valve-seat, said valve-casing including an apertured projecting portion, a closure-disk for one end of the casing, said closure-disk having a valve-stem bearing, a valve member comprising a valve-head for seating on the valve-seat, and a stem for passing through the valve-stem bearing of the closure-disk, a coil-spring surrounding said valve-stem and engaging the closure-disk to hold the valve with its head seated on the valve-seat, and a fire-shield interposed between the casing-web and the closure-disk, substantially as shown and described.

2. An engine of the character stated comprising a casing, fly-wheels rotatably mounted therein, a piston reciprocally mounted therein and connecting with the fly-wheels and dividing the casing into a first and a second chamber, said piston being arranged to draw the working agent into the first chamber while simultaneously compressing the charge in the second chamber, said casing having exhaust-apertures for said second chamber, means for exhausting the mixture in the second chamber as the piston reaches the end of its stroke, said piston being arranged to compress the charge of working agent in the first chamber as it moves under the influence of the exploded mixture, and means carried by the piston for opening up communication between the first and second chambers at predetermined times, said last-named means comprising a valve detachably connected to the piston and carried thereby, said valve comprising a casing having an internal web forming a valve-seat, said casing also including an apertured projecting portion, a closure-disk for one end of the casing, said closure-disk having a valve-stem bearing, a valve member comprising a valve-head for seating on the valve-seat, and a stem for passing through the valve-stem bearing of the closure-disk, a coil-spring surrounding said valve-stem and engaging the closure-disk to hold the valve with its head seated on the valve-seat, a fire-shield interposed between the casing-web and the closure-disk substantially as shown and described.

3. An engine of the character stated, comprising a casing, fly-wheels rotatably mounted therein, a piston reciprocally mounted therein and connecting with the fly-wheels

and dividing the casing into a first and a second chamber, said piston being arranged to draw the working agent into the first chamber while simultaneously compressing the charge in the second chamber, said casing having exhaust- 70

apertures for said second chamber, means for exhausting the mixture in the second chamber as the piston reaches the end of its stroke, said piston being arranged to compress the charge of working agent in the first chamber 75

as it moves under the influence of the exploded mixture, and means carried by the piston for opening up communication between the first and second chambers at predetermined times, said last-named means comprising 80

a valve detachably connected to the piston and carried thereby, said valve comprising a casing having an internal web forming a valve-seat, said casing also including an apertured 85

projecting portion, a closure-disk for one end of the casing, said closure-disk having a valve-stem bearing, a valve member comprising a valve-head for seating on the valve-seat, and a stem for passing through the valve-stem 90

bearing of the closure-disk, a coil-spring surrounding said valve-stem and engaging the closure-disk to hold the valve with its head seated on the valve-seat, a fire-shield interposed between the casing-web and the closure-disk, said fire-shield comprising a wire- 95

gauze member bent into a spherical shape, substantially as shown and described.

4. An engine of the character stated comprising the combination with the casing and a piston reciprocally mounted therein to divide 100

the casing into two compartments, of a valve on said piston for opening up communication between said two compartments at predetermined times, said valve comprising a cylindrical valve-casing having a screw-threaded 105

portion for co-operating with a screw-threaded aperture in the piston, said valve-casing having an internal apertured web arranged between the valve-casing ends and forming a 110

valve-seat, one end of said valve-casing being formed with an internal peripheral groove, a closure-disk seated in said groove, said closure-disk having a longitudinally-apertured bearing member, a valve having a head adapted to seat on said valve-casing seat and a stem adapted to pass through said disk-bearing 115

member, a spring surrounding said stem, said stem having a stop-head at its free end for engaging with said spring, and said spring adapted to hold the valve with its head on the 120

valve-seat, said valve-casing having a plurality of circumferential apertures, and a fire-shield disposed between said closure-disk and said valve-seat substantially as shown and described.

125

5. An engine of the character stated comprising the combination with a casing and a piston reciprocally mounted therein to divide the casing into two compartments, of a valve on said piston for opening up communication 130

between said two compartments at predetermined times, said valve comprising a cylindrical valve-casing having a screw-threaded portion for coöoperating with the screw-threaded apertures in the piston, said valve-casing having an internal web arranged between the valve-casing ends and forming a valve-seat, one end of said valve-casing being formed with an internal peripheral groove, a closure-disk seated in said groove, said closure-disk having a longitudinally-apertured bearing member, a valve having a head adapted to seat on said valve-casing seat and a stem adapted to pass through said disk-bearing member, a spring surrounding said stem, said stem having a stop-head at its free end for engaging with said spring, and said spring adapted to hold the valve with its head on the valve-seat, said valve-casing having a plurality of circumferential apertures, and a fire-shield between said closure-disk and said valve-seat, said internal web of the valve-casing having a groove to receive the peripheral edge of said fire-shield, and said fire-shield being centrally apertured to permit passage of the disk-bearing substantially as shown and described.

6. In an engine of the character stated, a pair of hollow fly-wheels arranged adjacent one another, drive-shafts upon which said fly-wheels are mounted, a casing for inclosing said fly-wheels and having bearing portions for said drive-shafts, a second casing detachably secured to said first casing, in communication therewith, a piston slidably mounted 35 in said second casing and dividing the same

into two chambers, a piston-rod connecting said piston with said fly-wheels, one of said chambers of the second casing forming an explosion-chamber, said casing having exhaust-apertures for said explosion-chamber closable 4c by said piston at predetermined times, a water-jacket surrounding said explosion-chamber, an automatically-operating valve carried by said piston for opening up communication between said first and second chambers at predetermined times, all being so arranged that the piston draws in a charge of working agent into the first chamber while simultaneously compressing a charge of working agent in the second or explosion chamber, means for exploding said charge in the explosion-chamber after it has become compressed to move the piston in an opposite direction to compress the charge within the first chamber, said piston being arranged to uncover the exhaust- 5c apertures as it reaches the end of its stroke under the influence of the exploded mixture to permit said exploded mixture to pass out of the explosion-chamber, and said piston-valve being arranged to open up communication between the first and second chambers to allow passage of the compressed charge of the first chamber into the second chamber as the burned mixture is exploded substantially as shown and described.
